UNITED STATES PATENT OFFICE.

WILLIAM H. NIEDERLUECKE, OF ST. LOUIS, MISSOURI.

TABLE-PAD.

1,389,567.

Specification of Letters Patent. Patented Aug. 30, 1921.

Application filed June 11, 1921. Serial No. 476,726.

To all whom it may concern:

Be it known that I, WILLIAM H. NIEDERLUECKE, a citizen of the United States, residing at city of St. Louis and State of Missouri, have invented new and useful Improvements in Table-Pads, of which the following is a specification.

My present invention pertains to table tops of the foldable type.

10 One object of the invention is the provision of a table pad susceptible of being expeditiously and easily folded into small compass.

15 Another object is the provision of a table pad embodying hinges that are, at once, simple and inexpensive and capable of withstanding considerable use.

20 Another object is the provision of an inexpensive table pad possessed of the capacity of preventing the transmission of heat from dishes to a fine table top.

25 Another object is the provision of a pad possessed of the capacity of cushioning and rendering noiseless the movement of dishes on a table as well as to protect a fine table top against scratching or other injury.

To the attainment of the foregoing, the invention consists in the improvement as hereinafter described and definitely claimed.

30 In the accompanying drawings, forming part of this specification:—

Figure 1 is a top plan view showing my novel pad as open.

Fig. 2 is an inverted plan view of the same.

35 Fig. 3 is an edge elevation of the pad as secured in open state.

Fig. 4 is an edge elevation of the pad as secured in folded state.

40 Figs. 5 and 6 are enlarged detail sections on the lines 5—5 and 6—6, respectively, of Fig. 1.

Fig. 7 is a perspective of one of the wire hinge members.

45 Fig. 8 is a perspective of the U-shaped holder member for retaining the pad in open state and also in closed state, Figs. 3 and 4.

Similar numerals designate corresponding parts in all of the views of the drawings.

50 Among other elements my novel table pad comprises three U-shaped hinge members 1. Each of these members 1 is formed of a single piece of wire and includes a longitudinal portion and end arms 2, as best shown in Fig. 7.

55 The pad also comprises a U-shaped holder member 3 best shown in Figs. 1, 3, 4 and 8.

The said holder member 3 is also formed by preference of wire in general U-shape, and its legs 4 are adapted to be sheathed in complementary sockets 5 and 6 in edges of the 60 pad sections as shown in Figs. 3 and 4; the holder member when used as shown in Fig. 3 serving to maintain the pad in a flat state, and when used as shown in Fig. 4 to retain a pad in a compact folded state for convenient 65 disposition or for storage or shipment.

The pad comprises four sections 7 which may be of rectangular form as shown or of any other configuration compatible with the purpose of my invention without involving 70 departure from the scope of the same as claimed. Each of the said sections 7 includes spaced walls 8 of pasteboard, a filler 9 of corrugated pasteboard, Figs. 5 and 6, and edge binding portions 10 of thin textile material connected by adhesive or other appropriate means to the pasteboard walls 8. By particular reference to Fig. 1 it will be noted that two flexible connecting strips 11, preferably of thin textile material are 80 used to hingedly connect the opposed edges of the sections 7 in the two pair of sections 7 illustrated, and by particular reference to Fig. 2 it will be observed that similar strips 12 are used to hingedly connect the opposed 85 edges of the sections in the pads; the strips 12 being disposed at right angles to the strips 11 so as to permit of the pad being folded in two directions into the compact bundle shown in Fig. 4, and the strips 11 90 and 12 being connected to the sections 7 by adhesive or other appropriate means. In the described hinging of the sections 7 the strips 11 and 12 are associated by the before described hinge members 1, relatively arranged as shown in Fig. 2; each of the 95 said members 1 having its arms 2 socketed in one of the sections 7 as shown by dotted lines in Figs. 1 and 2, and also having its longitudinal portion arranged in a barrel 100 13, Fig. 5, and formed of a strip of material that straddles the adjacent edge of the opposed section 7 and is connected thereto by adhesive or other appropriate means.

It will be apparent from the foregoing 105 that notwithstanding its capacity in serving the purposes ascribed to it, my novel pad is adapted to be inexpensively and easily produced without the employment of expensive machinery so that the pad can be sold with 110 profit for a small price.

I have entered into a detailed description

of the construction and relative arrangement of parts embraced in the present and preferred embodiment of my invention in order to impart a full, clear and exact understanding 5 of the said embodiment. I do not desire, however, to be understood as confining myself to the said specific construction and relative arrangement of parts inasmuch as in the future practice of the invention various changes and modifications may be 10 made such as fall within the scope of my invention as defined in my appended claims.

Having described my invention, what I claim and desire to secure by Letters-Pat- 15 ent, is:-

1. A foldable table pad comprising sections, U-shaped hinge members and flexible strips hingedly connecting the said sections, said U-shaped members having arms socketed in the edge portions of sections, and

barrels connected to the opposed edges of other sections and receiving the longitudinal portions of the U-shaped members.

2. A foldable table pad comprising sections, U-shaped hinge members and flexible strips hingedly connecting the said sections, 25 said U-shaped members having arms socketed in the edge portions of sections, and barrels connected to the opposed edges of other sections and receiving the longitudinal 30 portions of the U-shaped members, said sections having sockets in their edges, in combination with a U-shaped holder member having legs to be arranged in said sockets to retain the pad in an open state and in a 35 folded state, alternately.

In testimony whereof, I affix my signature.

WILLIAM H. NIEDERLUECKE.
